OF NEW YORK.

FORGING FOR CAR-TRUCK SIDE FRAMES.

1,083,392.

Specification of Letters Patent.

Patented Jan. 6, 1914.

Application filed June 16, 1913. Serial No. 773,856.

To all whom it may concern:

Be it known that I, WILLIAM D. FORSYTH, a citizen of the United States, residing at Youngstown, in the county of Mahoning and State of Ohio, have invented new and useful Improvements in Forgings for Car-Truck Side Frames, of which the following is a specification.

This invention relates to forgings for car truck side frames made from a single piece of rolled metal.

One of the objects of this invention is to provide a forging of such cross section that the metal may be distributed in the top and bottom members of the forging, and the bolster opening therein may be so placed as to make said top and bottom members more effective as to strength and clearance between the car body and the top of the rails of the track, the position of the bolster opening coöperating with the distribution of the metal in the top and bottom members of the forging to permit the clearance between the car body and the top of the rails, as aforesaid, to be more effectively adjusted.

The invention consists, among other things, of a forging for a car truck side frame made from a single piece of metal, consisting of a rolled section having two flanges connected by a web, with unequal amounts of metal in said flanges and a bolster opening made in said web by slotting the same along its longitudinal axis, between the ends of said web, removing from said web a part thereof between the upper edge of said slot and the lower side of the top flange of the section and expanding said web substantially at right angles to said slot; with the ends of both top and bottom flanges arranged so that they shall be over the top of the axle of the car to which the car truck side frame into the construction of which said forging enters, is attached, as herein more specifically described.

In the accompanying drawings, Figure 1 is a rolled metal section; Fig. 2 is an end view of Fig. 1; Fig. 3 is a side view of Fig. 1, with the flanges and web cut and punched preparatory to expansion; Fig. 4 is a forging after the same has been expanded and the lower flange conformed to the free outer edges of the web and the undersides of the top flange.

Like figures of reference refer to like parts throughout.

In Fig. 1, 1 is a rolled section, having a top flange 2; a web 3; a bottom flange 4, which is rolled so as to have the cross section shown in Fig. 2; the top flange 2 having a longitudinal groove 2' throughout its length, and while bottom flange 4 has not said longitudinal groove, it may have such longitudinal groove indicated by dotted lines 4' in Fig. 2. Preparatory to expanding said rolled section, web 3 is cut away between the ends of the flanges; top flange 2 is made shorter than bottom flange 4; slot 5 is made in the central part of said web, and that part 5' of the web, between the underside of top flange 2, the top of slot 5 and vertical lines 6, 6, is punched out so that the rolled section 1 shall take the form shown in Fig. 3. The rolled section 1 as thus formed, either while hot or cold, by suitable apparatus is pressed so that the web thereof shall be expanded substantially at right angles to slot 5, and so that the top and bottom flanges shall take the form shown in Fig. 4. When this formation has taken place, top flange 2 has a central part 7 at ends 8, 8, connected by downwardly extending parts 9, 9, and bottom flange 4 has a central part 10 at ends 11, 11, connected to central part 10 by downwardly extending parts 12, 12. The ends 11 of 4 are so bent as to contact with the edges 13, 13, of the web and the undersides of the ends 8, 8, of the top flange 2, between points 14 and 15; the expansion of the web, as aforesaid, causes the formation of the bolster opening 16 in the forging.

The flange 2, consisting of central part 7 and ends 8, 8, connected by downwardly inclined parts 9, 9, will constitute the compression member of any car truck side frame into the construction of which the forging herein described enters, and bottom flange 4, consisting of central part 2 and ends 11, connected by upwardly extending parts 12, 12, will constitute the tension member in such car truck side frame.

In Fig. 4 the dotted lines 17, 17 and 18, 18, indicate the bottom of the groove 2' in the top flange and the bottom of the groove 4' in the bottom flange, if said bottom flange be made with said groove. Any of the metal of said flanges above dotted lines 17, 17, or below dotted lines 18, 18, may be removed. For instance, if the metal be removed between points 19, 19 on the top flange, if the groove 2' in said flange be an inch and a

half deep, it will afford clearance to that extent between the car body of the car and the top of the car truck side frame in which said forging may be used, and if in like manner the metal in the bottom flange, between points 20, 20, be removed, it will afford clearance to the depth of groove 4' therein, between the bottom of the forging and the top of the rail. The removal of a part of the web at 5' enables an adjustment of the bolster of the car truck in which the forging is used in a vertical line and at the same time permits the retention of the entire web between its outer free edges along the bottom flange 4.

If the cross section of bottom flange 4 be solid, as indicated in the solid lines in Fig. 2, and it is desired to decrease the weight of the forging and at the same time retain the metal section through the web and the bottom flange at its greatest depth, metal can be removed from below dotted lines 21, 21, by any preliminary preparatory operation.

While I have shown in Fig. 2 specific cross sections for the top and bottom flanges of the rolled section, any cross section may be used which will permit a different distribution of metal, either along the entire length of said top and bottom flanges or at intervals along their lengths.

What I claim as my invention is:

1. A new article of manufacture, a forging for a car truck side frame made from a single piece of metal, having a web integral with two parallel flanges of different lengths and cross-sections and shorter than both flanges, said web having an opening therein formed by cutting away a part of the same about midway between the ends of the shorter flange and substantially along its under surface and over and along a line about midway between said flanges; said web being expanded in direction substantially at right angles to said flanges, said longer flange being bent at both ends so as to contact with and conform to the free edges of said web and the under sides of the ends of the short flange.

2. A car truck side frame made from a single piece of metal, having a compression member, a tension member longer than said compression member, said members being connected by a web having a bolster opening made therein by expanding said web in direction substantially at right angles to said members; said web extending continuously along said tension member between points distant from its ends and in two parts along said compression member between points distant from its ends and points in the sides of said bolster opening.

3. A car truck side frame made from a single piece of metal, having a compression member, a tension member longer than said compression member, said members being

connected by a web having a bolster opening made therein by expanding said web in direction substantially at right angles to said members; said web extending continuously along said tension member between points distant from its ends and in two parts along said compression member between points distant from its ends and points in the sides of said bolster opening, both ends of the tension member being bent to contact with the outer edges of said web and the ends of the compression member.

4. A car truck side frame made from a single piece of metal, having a compression member, a tension member longer than said compression member, said members having different cross-sections, said members being connected by a web having a bolster opening made therein by expanding said web in direction substantially at right angles to said members; said web extending continuously along said tension member between points distant from its ends and in two parts along said compression member between points distant from its ends and points in the sides of said bolster opening.

5. A car truck side frame made from a single piece of metal, having a compression member, a tension member longer than said compression member, said members having different cross-sections, said members being connected by a web having a bolster opening made therein by expanding said web in direction substantially at right angles to said member; said web extending continuously along said tension member between points distant from its ends and in two parts along said compression member between points distant from its ends and points in the sides of said bolster opening, both ends of the compression member being bent to contact with the outer edges of said web and the ends of the compression member.

6. A new article of manufacture, a forging for a car truck side frame made from a single piece of metal, having a web integral with two parallel flanges of different lengths and cross-sections at intervals along their lengths and shorter than both flanges, said web having an opening therein formed by cutting away a part of the same about midway between the ends of the shorter flange and substantially along its under surface and over and along a line about midway between said flanges; said web being expanded in direction substantially at right angles to said flanges, said longer flange being bent at both ends so as to contact with and conform to the free edges of said web and the under sides of the ends of the short flange.

7. A car truck side frame made from a single piece of metal, having a compression member, a tension member longer than said compression member, said members having different cross-sections at intervals along

their lengths, said members being connected by a web having a bolster opening made therein by expanding said web in direction substantially at right angles to said members; said web extending continuously along said tension member between points distant from its ends and in two parts along said compression member between points distant from its ends and points in the sides of said bolster opening.

8. A car truck side frame made from a single piece of metal, having a compression member, a tension member longer than said compression member, said members having different cross-sections at intervals along their lengths, said members being connected by a web having a bolster opening made therein by expanding said web in direction

substantially at right angles to said member; said web extending continuously along said tension member between points distant from its ends and in two parts along said compression member between points distant from its ends and points in the sides of said bolster opening, both ends of the compression member being bent to contact with the outer edges of said web and the ends of the compression member.

In witness whereof I have hereunto subscribed my name in the presence of two subscribing witnesses.

WILLIAM D. FORSYTH.
